UNITED STATES PATENT OFFICE.

AUGUSTUS LOTZ, OF SAN FRANCISCO, CALIFORNIA, ASSIGNOR OF ONE-HALF
TO JOSEPH HAAS AND JULIUS KAHN, OF SAN FRANCISCO, CALIFORNIA.

APPARATUS FOR CLEANING CARPETS.

SPECIFICATION forming part of Letters Patent No. 695,162, dated March 11, 1902.

Application filed December 4, 1900. Serial No. 38,602. (No model.)

To all whom it may concern:

Be it known that I, AUGUSTUS LOTZ, a citizen of the United States, residing in the city and county of San Francisco and State of California, have invented certain new and useful Improvements in Apparatus for Cleaning Carpets; and I do hereby declare the following to be a full, clear, and exact description of the same.

10 The objects of the present invention are to provide an apparatus by means of which carpets may be cleaned while upon the floor and the debris or refuse automatically removed, thus obviating the necessity of removing the carpet from the floor and saving wear and tear resulting thereto by the beating of the carpet in order to remove the dirt; to provide an apparatus by means of which dry or super-heated steam, compressed air, gases, or vapors may be employed as the vehicle for removing the dust or dirt from the carpet; to provide an apparatus by means of which the carpet may not only be cleaned while upon the floor, but which will permit of disinfectants to be applied thereto and the carpet perfectly disinfected, and in providing an apparatus by means of which the carpet may be thoroughly cleaned without damage thereto.

To comprehend the invention, reference 30 should be had to the accompanying sheets of drawings, forming a portion of this application, wherein—

Figure 1 is a side view in elevation of the apparatus, partly broken. Fig. 2 is a top plan view of the mechanism illustrated in Fig. 1. Fig. 3 is a vertical sectional view in side elevation, taken on line $x-x$, Fig. 2; and Fig. 4 is a view similar to Fig. 1, illustrating the suction-pipe as being connected to a dust-ar- 40

rester. In the drawings the letter A is used to indicate any suitable form of a casing or housing, which is formed with an interior dia- phragm or partition A'. This diaphragm or partition serves to form a passage-way a, with which communicates the supply-pipe A², through which pipe air under pressure is con-veyed from a compressor (not shown) to the said passage-way a. The lower end of the 50 front wall A³ of the casing or housing is in-

clined inwardly, thus contracting the lower end of the passage-way a, so as to leave only a jet orifice or opening b, through which the air under pressure may escape. It will be understood that this jet orifice or opening 55 preferably extends the entire width of the casing or housing proper.

The bottom plate B of the casing or housing extends to within a short distance of the inner face of the diaphragm or partition A' 60 in order to provide what I shall term a "de- livery-opening" b', which opening communi- cates with the receiving-chamber B' of the casing or housing. The forward edge of the bottom plate B terminates in a downwardly- inclined lip b², which, as will be hereinafter explained, serves to raise the pile of the carpet or material being treated in order that the air-blast may penetrate the same and the dirt be freed therefrom.

A suction-pipe B³ communicates with the receiving-chamber, which pipe connects with a suction-pump. (Not shown.) In the present case the suction-pipe is illustrated in connection with a dust-arrester C, Fig. 4. Any 75 suitable form of arrester may be employed for the purpose of collecting the dust removed from the carpet or material being cleaned. However, I have illustrated an extremely sim- ple form of an arrester, the same consisting of a 80 sealed receptacle divided into a series of compartments—say three—1 2 3. The suction-pipe discharges into compartment 1, the heavier particles of the discharged material set- tling therein and the lighter particles be- 85 ing conveyed into compartment 2 through connecting-pipe. In this compartment the heavier particles of the discharged debris will settle and the lighter particles be conveyed into compartment 3 through connecting-pipe. 90 This compartment is partly filled with wa- ter, and the end of the connecting-pipe is submerged therein. Consequently all foreign matter contained within the air discharged therein is collected by the body of water. 95 Hence the air drawn from this compartment is freed of all impurities. The pipe connec- tions between the compartments I treat as continuations of the suction-pipe, it being un- derstood that that portion leading from com-

partment 3 connects with the suction-pump, situated at any point convenient to the work being done.

The casing or housing is in the present case moved back and forth over the carpet C' or material to be cleaned by means of the handle C², the arms C³ of which are hinged to the side walls of the said casing or housing. This handle supports the valve-rod D, the upper end of which is attached to the finger-piece D', fulcrumed to the said handle. The lower end of the valve-rod is connected to the rotatable valve D² by means of the crank-arm D³. The valve D² works within the seat d and serves to open and close the passage-way a, so as to control the flow of compressed air. The valve-rod is normally held pressed outward by the spring E, so that the valve will close the passage-way a against admission of air through port d' of the valve. To open the valve, it is only required that pressure be exerted upon finger-piece D', which throws the valve-rod D downward and through its connection with the valve D² turns the valve so as to place its port d' in registry with passage-way a.

The connection between the supply-pipe, suction-pipe, and the casing or housing is preferably a detachable one, the supply-pipe being secured in the present case to boss 4 and the suction-pipe to boss 5.

As stated, supply-pipe A² leads from a compressor and suction-pipe B³ from any suitable suction pump or mechanism. These parts may be located at any suitable point. If desired, they may constitute a central station or be located immediately outside of the building wherein the carpets are being cleaned. It is obvious that the invention is not confined to the use of compressed air, for superheated steam, dry steam, gases, or any fluid vapor may be employed. Consequently I do not wish to be understood as confining myself to mechanism for the use of compressed air, for by such expression it is my intent to cover any and all forms of mechanism by means of which vapor or volatile fluids may be applied to and withdrawn from the material to be cleaned for the purpose of removing the dirt therefrom.

The invention is not only designed for use in connection with the cleaning of carpets, but is equally applicable to the cleaning of rugs, mats, or any fabric having the characteristics of carpet or rugs.

While the invention is mainly designed for the cleaning of carpets without removing same from the floor, it is not limited to such use, and I am well aware that, if so desired, the apparatus may be of the form of a "stationary plant," by which is meant an establishment for the cleaning of such goods and the material to be treated brought to the machine for treatment.

In the operation of cleaning, where the carpet is treated without removal, the casing or housing is passed back and forth over the sur-

face of the carpet, the operator propelling same by means of the handle C². It will be understood that when in use the valve D² is turned to open communication between the supply-pipe and passage-way a. As moved over the surface of the carpet air or steam or vehicle employed is ejected from jet orifice or opening b under pressure into the pile of the carpet and forces the dirt and dust therefrom through feed-opening b' into the receiving-chamber B'. From this chamber the dust and dirt are withdrawn through suction-pipe B³. During the movement of the apparatus the lip b² of bottom plate B engages the pile of the carpet and raises same in order that air may thoroughly penetrate and bear upon the body thereof, thus insuring the removal of all dust or dirt. The pressure of air may be cut off at will by simply releasing the pressure upon finger-piece D', when the tension of spring E will force the valve-rod upward and turn valve D² so as to cut off the supply of air.

All dust or dirt drawn from the receiving-chamber is discharged into the arrester C, interposed between the apparatus and suction-pipe, so that dirt or foreign matter is removed from the air prior to the discharge thereof.

As it is possible that some of the dust or dirt forced from the carpet may escape, a hood E' is provided. This hood surrounds the lower portion of the casing or housing A and forms an auxiliary chamber E², which receives any dust, dirt, or impregnated air that may escape. This chamber communicates with receiving-chamber B' by means of the openings d² in the side walls of the casing or housing A. Consequently any dirt or dust escaping into the auxiliary chamber is sucked into the receiving-chamber through side openings d².

To prevent marring of the furniture or woodwork within the room, a rubber band E³ is secured to the hood, as shown.

The apparatus designed for cleaning of carpets upon the floor in size and form is substantially the same as the ordinary carpet-sweeper.

It will be understood that by the expression "casing or housing" as used in this application is meant a body, frame, base, or support by means of which the air supply and exhaust mechanisms are connected.

Having thus described the invention, what is claimed as new, and desired to be protected by Letters Patent, is—

1. The combination with a casing or frame, of an air-inlet passage-way therethrough, said passage-way terminating in a contracted outlet, a receiving-chamber having a feed-opening therein, of means whereby air under pressure is supplied to the passage-way and ejected against the material being treated with sufficient force to remove dirt and foreign matter therefrom and force same into the receiving-chamber, means whereby the material delivered into the receiving-chamber is automatically removed therefrom, a hood E' surround-

ing the casing so as to form an auxiliary chamber for collecting any dust or dirt which may escape, and of communication between said chamber and the receiving-chamber.

5 2. The combination in an apparatus for cleaning carpets or similar material, of a casing or frame, of a receiving-chamber in said casing or frame, an air passage-way extending through the casing, of means for supplying air to said passage-way and forcing the same against the carpet with sufficient force to eject the dust and dirt therefrom and deliver same to the receiving-chamber, mechanism whereby the air and dirt are automatically removed from the receiving-chamber, of means for propelling the casing over the surface of the carpet to be cleaned, a valve in the air-supply, and means operatively associated with the propelling means for operating said valve.

3. In an apparatus for the purpose described, the combination with the casing, of a hand device by means of which it is propelled over the carpet to be cleaned, of means for forcing a current of air against the surface of the carpet with sufficient force to eject the dust and dirt therefrom, valve mechanism by means of which the air-supply is controlled, means connected to the hand device for operating the valve mechanism and of means whereby the utilized air and dust ejected from the carpet are automatically removed.

4. The combination, in an apparatus for cleaning carpets or similar material, of a casing or frame, of a receiving-chamber in said casing or frame, a downwardly-projecting lip b^2 at the bottom of said chamber, an air passage-way extending through the casing, of means for supplying air to said passage-way and forcing the same against the carpet to eject the dust and dirt therefrom and deliver the same into the receiving-chamber, and means for automatically removing the dust and dirt from the receiving-chamber, substantially as described. 45

5. The combination in an apparatus for cleaning carpets or similar material, of a casing or frame, of a receiving-chamber in said casing or frame, an air passage-way extending through the casing, of means for supplying air to said passage-way and forcing the same against the carpet to eject the dirt and dust therefrom and deliver the same into the receiving-chamber, means for automatically removing the dust and air from the receiving-chamber, and a hood E' surrounding the casing and communicating with the receiving-chamber, substantially as described. 55

In witness whereof I have hereunto set my hand.

AUGUSTUS LOTZ.
